UNITED STATES PATENT OFFICE.

JOHN S. KIDD, OF DES MOINES, IOWA.

WAGON-DUMP AND ELEVATOR.

SPECIFICATION forming part of Letters Patent No. 449,680, dated April 7, 1891.

Application filed August 31, 1888. Renewed August 20, 1889. Again renewed August 11, 1890. Serial No. 361,639. (No model.)

To all whom it may concern:

Be it known that I, JOHN S. KIDD, a citizen of the United States of America, and a resident of Des Moines, in the county of Polk and State of Iowa, have invented an Improved Wagon-Dump and Elevator, of which the following is a specification.

My invention consists in the construction and combination of a dumping-platform, an elevator-frame, an elevator-box, and mechanism for operating the platform and raising and lowering the elevator, as hereinafter set forth, pointed out in my claims, and illustrated in the accompanying drawings, in which—

Figure 1 is a side view of the complete machine, showing the elevator-box suspended and a hinged section of the platform adjusted as required to allow the box to descend to the ground. Fig. 2 is a top view of the platform and the operative devices combined with the platform. Fig. 3 is an enlarged side view of a section of the dumping-platform and operative mechanism combined therewith. Fig. 4 is a top view of the top portion of the elevator-frame, and Fig. 5 is an end view of the same frame. Fig. 6 is a top view of the frame upon which the elevator-box is operated, and Fig. 7 is a side view showing the box upon said frame.

A are the sills of the elevator-frame.

A² are extensions hinged to the ends of the sills in such a manner that they can be turned upward, so that the complete sills may be used as runners for moving the frame and complete machine from one place to another.

A³ are posts fixed to the ends of the sills A.

A⁴ represents the platform-frame fixed to the sills A.

A⁵ are cross-pieces fixed to the tops of the posts A³.

A⁶ are braces that extend from said cross-pieces to the platform-frame, and A⁷ are braces that extend from the same cross-pieces to the posts A³.

B is a section of the platform, connected with the frame A⁴ in such a manner that it can be tilted as required to dump a load from a wagon resting thereon.

B² are metal segments or rockers, preferably toothed, fixed to the side pieces of the section B to engage straight or curved toothed bars or racks B³, fixed to the frame A⁴. While the central portion of the tilting section is thus supported, when a loaded wagon is upon it the wagon is backed and the rear end of the tilting section and wagon descends and their front ends ascend, as required, to dump the contents into the elevator-box, and the front end of the section and the wagon will rise faster and a greater distance, and the rear end of the section and wagon will descend, and consequently the dumping-platform can be lower, than when the tilting section has a stationary pivot.

C is a hinged and reversible section of the tilting platform B at its rear end.

C² is a wheel-scotching block or bar fixed on its top in such a manner that it will restrict the backward motion of a wagon and prevent the wagon-wheels from running off the tilting section when the section is inclined as required to dump the contents of the wagon into the elevator-box.

C³ are iron bars fixed on top of the section C to extend outward in such a manner that when said hinged section is inverted, as indicated by dotted lines in Fig. 3, they will project under a fixed incline C³ and aid in uniting the two parts to produce a bridge over which a loaded wagon can be advanced to the top of the tilting section.

C⁴ is a frame hinged to the ends of the sill-extensions A², and C⁵ is a fixed floor that connects with the sections C and C³ when the frame is lowered to produce a complete inclined plane over which a wagon can be advanced from the ground to the top of the tilting platform-section C.

F is the frame that supports the elevator-box. It is suspended from the top of the elevator-frame by means of four ropes F², that pass over pulleys F³, attached to the cross-pieces A⁵ at the top of the frame at four different points, as shown in Fig. 4.

F⁴ are triple-grooved directing-pulleys, over which the ropes F² are passed downward and connected with chains H, (by tying or in

any suitable way,) which chains are extended over sprocket-wheels and connected with cables that are passed over the triple-grooved pulleys F^4 and fastened to the platform.

5 H' are wire ropes connected with the ends of the chains to produce endless flexible devices that will be operated by means of sprocket-wheels in such a manner that the rope portions will be constantly on the pulleys F^4 , while the chains are constantly on the sprocket-wheels H^2 . By thus combining the ropes F^2 and H' with the chains H comparatively short pieces of chains and shorter ropes are required and the cost of construction of the complete hoisting mechanism reduced, while its efficiency is improved.

10 H^2 are sprocket-wheels fixed to an axle H^3 , that has its bearings fixed to the frame A in such a manner that when the axle is rotated 20 the ropes F^2 on the pulleys F^3 will be lengthened or shortened, as required, to raise or lower the frame F.

15 J is a drum fixed to the axle H^3 .

20 J^2 is a rope fixed to the drum J and extended over a directing-pulley J^3 , attached to the frame A in such a manner that when a horse is hitched to the end of the rope, or other power applied to pull on the rope, it will rotate the drum and the two sprocket-wheels H^2 as required to operate the chains H and ropes F^2 , and thereby elevate the frame F and a loaded box upon the frame.

25 L is an elevator-box supported upon the frame F. The central portion of its bottom is flat and the end portions inclined.

30 m are metal rockers, flat-bottomed and straight at their central portions and curved and toothed at their end portions, fixed to the outside faces and centers of the box.

35 m' are straight or curved metal bars or racks fixed to the side pieces of the frame F in such a manner that the metal rockers m will rest level thereon and support the box level, but allow it to be tilted and its contents emptied from either one of its ends by means of ropes 40 m'' , attached to the ends of the box. By thus making the central portions of the rockers straight the loaded box will remain stationary and balanced in its normal condition, so 45 that a locking device for retaining it stationary upon its movable support is not required.

50 m''' are ropes detachably connected with the frame F and hinged end-gates at the ends of the box in such a manner that they can be readily adjusted as required to keep one end closed while the box is being tilted and the other end opened at the same time.

55 n is a shaft in bearings fixed to the frame A. It has fixed drums n' , to which ropes n'' are attached and extended upward and over pulleys n''' and then down and fastened to the tilting section B of the platform in such a manner that the front end of the tilting section can be lifted by rotating the shaft by 60 means of a crank-handle on its end.

65 r is a ratchet-wheel fixed to the shaft n , and

r' is a pawl pivoted to the frame A in such a manner that the shaft can be locked, as required, to retain the tilting section and a wagon thereon elevated at their front ends as long as may be necessary to allow the contents of the wagon to be discharged into the elevator-box when it is resting upon the ground at the rear end of the platform and wagon.

70 I claim as my invention—

75 1. The elevator-frame and platform-frame composed of the sills A, hinged extensions A^2 , posts A^3 , having cross-pieces A^5 at their top ends, the platform-frame A^4 , and the braces A^6 and A^7 , arranged and combined substantially as shown and described, for the purposes stated.

80 2. A wagon-dumping platform carrying a wheel-scoching or wagon-holding device and provided with rockers fixed to its sides, in combination with a frame and base having fixed straight bars adapted to engage the said rockers, and mechanism for operating the platform to empty the contents of the wagon-box.

85 3. A platform-frame having fixed racks B^3 near one end and a floor adapted to support horses at the other end, and a platform B, having fixed segments B^2 , adapted to engage the fixed racks on the frame, and mechanism for lifting the end of said platform B, arranged and combined substantially as shown and described, for the purposes stated.

90 4. A hinged invertible platform-section having a wheel-scoching bar or block fixed on its top, in combination with a wagon-dumping platform having a fixed floor under the hinged section, for the purposes stated.

95 5. The hinged platform-section C, having the fixed bar C^2 , in combination with a platform having a fixed inclined floor at its end, for the purposes stated.

100 6. The hinged frame C^4 , having a fixed floor C^5 , in combination with a platform having an invertible hinged section C to produce an inclined bridge or driveway to the top of a wagon-dumping platform.

105 7. An elevator-box having fixed bars that are straight at their central portions and curved at their end portions, in combination with a frame having fixed bars adapted to support the bars fixed to the elevator-box, for the purpose of operating the box in the manner set forth.

110 8. The elevator-box L, having fixed rockers m and hinged end-gates, the frame F, having fixed bars m' , ropes m'' , and the adjustable ropes m''' , arranged and combined to operate in the manner set forth, for the purposes stated.

115 9. In a wagon-dump and elevator, the combination of an endless belt consisting in part of a chain adapted to engage a sprocket-wheel and a rope adapted to engage a pulley, a sprocket-wheel on a rotating shaft located at the lower part of the complete machine, a triple pulley on a shaft located at the upper portion of the elevator-frame, and two

ropes connected with the said endless belt and extended over the said triple pulley, for the purpose stated.

10. The shaft H³, having a fixed drum J and fixed sprocket-wheels H², the chains H, having ropes H' fixed to their ends, the pulleys F³ and F⁴, and the ropes F², connected with a suspended elevator-box, arranged and com-

bined with an elevator-frame and wagon-dumping platform to operate in the manner set forth, for the purposes stated.
